UNITED STATES PATENT OFFICE.

JOHN ADOLPH ETTLER, OF SAN ANTONIO, TEXAS.

DESIGN FOR A BINDER FOR PLASTER, &c.

SPECIFICATION forming part of Design No. 31,795, dated November 7, 1899.

Application filed October 14, 1899. Serial No. 733,678. Term of patent 3½ years.

To all whom it may concern:

Be it known that I, JOHN ADOLPH ETTLER, a citizen of the United States, residing at No. 817 South Presa street, San Antonio, in the county of Bexar and State of Texas, have invented and produced a new and original Design for a Metal Binder for Plaster, Concrete, &c., of which the following is a specification.

The invention relates to a new and original design for a binder for plaster, concrete, &c.

The essential feature of the design resides in a binder provided with parallel corrugations forming reversely-arranged dovetailed ribs projecting alternately from opposite sides and having inner and outer approximately V-shaped bends in their walls.

In the drawings, Figure 1 is a perspective view of a metal binder, showing my new and original design. Fig. 2 is a cross-section of the same.

Referring to the drawings, 1 designates a sheet-metal binder provided at regular intervals with parallel corrugations 2, forming reversely-arranged parallel ribs 3, projecting alternately from the opposite sides or faces of the

binder, as clearly illustrated in Fig. 2 of the accompanying drawings. The outer faces 4 of the ribs are flat, and those at the same side or face of the binder are arranged in the same plane, and the said ribs have a general taper 30 toward their outer flat faces 4. The walls or sides of each rib are provided with angular bends forming inner and outer V-shaped recesses 5 and 6. The space inclosed by the sides or walls of each rib of one side of the 35 binder forms the corrugation of the opposite side of the binder, and the said bends form reversely-arranged recesses at the corrugation.

What is claimed is—

The design for a binder, as herein shown and described.

In testimony that I claim the foregoing as my own I have hereto affixed my signature in the presence of two witnesses.

JOHN ADOLPH ETTLER.

Witnesses:

G. W. ALLEN,
W. P. ALLEN.
